UNITED STATES PATENT OFFICE.

OSCAR LOEWENBACH, OF MILWAUKEE, WISCONSIN.

LOOSE-LEAF BINDER.

Application filed July 14, 1927. Serial No. 205,619.

This invention relates to loose leaf binders. Objects of this invention are to provide a novel form of loose leaf binder in which a holding plate is provided and retained by extremely simple and easily manipulated means so that the holding plate may be slid over posts carried by the back of the binder and will automatically lock in place and may be as easily released, although it will securely hold against inadvertent detachment.

Further objects are to provide a loose leaf binder in which a rigid back is provided with projecting posts adapted to receive the loose leaves, and in which means are provided co-operating with a locking bar to retain the leaves against tearing or disturbances when the locking bar is removed.

An embodiment of the invention is shown in the accompanying drawings in which:

20 Figure 1 is a plan view of the binder;
Figure 2 is a sectional view on the line 2—2 of Figure 1;

25 Figure 3 is a sectional view on the line 3—3 of Figure 1.

It is to be distinctly understood that the sectional views have been greatly exaggerated to more clearly show the invention.

Referring to the drawings, it will be seen that the loose leaf binder comprises a rigid back 1 which may be suitably covered and which is preferably provided with a reinforcing bar 2 at one edge. This bar 2 carries a pair of upwardly extending rigid posts 3 which are adapted to receive loose leaves, such as shown at 4. The posts 3 slidably and loosely receive a pressure bar or auxiliary bar 5 which fits over the posts and may be dropped down upon the loose leaves 4. This bar 5 is relatively thick and heavy and cannot be distorted. Above the bar 5, a locking bar or plate 6 is provided and is of relatively thinner metal, as indicated in the drawings, and is provided with inwardly turned ends 7. The plate is apertured, as indicated at 8, for the reception of the posts 3 and also is provided with a pair of outwardly projecting spring fingers 9. These spring fingers are apertured, as indicated at 10 for slidably receiving the posts. It is to be noted, however, that when the bar 6 is slid into place upon the posts, that it may be slightly bowed, as shown in Figure 2, and that the springs or resilient strips 9 will also be bowed.

Further, it is to be noted that the posts 3 bear against the outer edge of the aperture 8 in the bar 6 and against the inner edge of the

aperture 10 in the strips 9. The strips 9 freely yield to permit sliding inwardly or downwardly upon the posts, but resist any upward motion as they thrust the posts into 60 tighter engagement with the outer portion of the apertures 8 in the strips 6 and thus automatically lock the strip 6 in place.

In using the device, it is merely necessary to position the loose leaves 4 upon the posts 3 and slip the bar 5 in place. Thereafter, the operator slides the bar 6 over the posts and automatic locking, as described above, takes place. It is to be noted that the feet 7 or in-turned ends of the bar or strip 6 maintain the 70 outer portions of the bar elevated, and consequently cause the bar 6 to bow downwardly in the middle. Thus, when the bar 6 is locked in place, it imparts pressure to the auxiliary or pressure bar 5 at spaced points, for instance, in the middle and at each end, as shown in Figure 2. Thus, the loose leaves are held by a uniform pressure throughout their entire edge portions, as the bar 5 cannot be distorted, as it is of material thickness and rigidity. 80

It is preferable in devices of this type to provide a pocket formed by means of a flap 11 secured to the rigid back 1 or bottom of the binder. This pocket is for the reception of the rigid back 12 of a stack or block of sheets 13, as shown most clearly in Figure 3. Under these conditions, the posts 3 and the locking or binding mechanism described, may be used to hold a plurality of carbon sheets 4. If desired, a cutout portion 14 may be formed in 90 the back, as shown in Figure 1, to facilitate positioning and removal of the block of sheets. The unused carbon sheets 4 may be temporarily stored or positioned beneath the lowermost of the sheets 13. 95

It is obvious that the device is capable of numerous other uses, one only having been described and illustrated in order to fully disclose the invention.

It is intended therefore that this mode of 100 describing the invention be interpreted as merely illustrative and in no sense limiting.

It will be seen therefore that although the invention has been described in considerable detail, such description is intended as illustrative rather than limiting as the invention may be variously embodied and as the scope of such invention is to be determined as claimed.

I claim:

1. A loose leaf binder comprising a back 110 having projecting posts extending therefrom adapted to receive loose leaves, and a locking

bar apertured for the reception of said posts and having a pair of upwardly extending slanting spring fingers apertured for the reception of said posts, said spring fingers binding said posts against the walls of the apertures in said bar and being releasable by causing relative motion between the ends of the spring fingers and said bar.

2. A loose leaf binder comprising a back provided with projecting posts adapted to receive loose leaves, a pressure bar apertured for free reception upon said posts, a locking bar having apertures for receiving said posts, said locking bar having outwardly extending upwardly projecting spring fingers apertured for the reception of said posts, said spring fingers binding against the inner side of said posts and forcing said posts against the outer sides of the apertures in said last mentioned bar.

3. A loose leaf binder comprising a back provided with projecting posts adapted to receive loose leaves, a pressure bar apertured for free reception upon said posts, a locking bar having apertures for receiving said posts, said locking bar having outwardly extending upwardly projecting spring fingers apertured for the reception of said posts, said spring fingers binding against the inner side of said posts and forcing said posts against the outer sides of the apertures in said last mentioned bar, said last mentioned bar being inwardly bowed adjacent its center and bearing at its center and at its ends against the first mentioned bar.

4. A loose leaf binder comprising a rigid back, a pair of posts projecting upwardly therefrom and adapted to receive loose leaves, a pressure bar of rigid construction freely

slidably positioned upon said posts and adapted to bind against said loose leaves, a locking bar having inwardly turned ends and having a downwardly bowed center, said locking bar being apertured for the reception of said posts, a pair of upwardly and outwardly extending spring fingers apertured for the reception of said posts, said spring fingers bearing against the inner sides of said posts and forcing said posts against the outer side of the walls of the apertures in said locking bar, said locking bar engaging said pressure bar at a plurality of spaced points.

5. A loose leaf binder comprising a rigid back, a pair of posts projecting upwardly therefrom and adapted to receive loose leaves, a pressure bar of rigid construction freely slidably positioned upon said posts and adapted to bind against said loose leaves, a locking bar having apertures adjacent its ends and having downwardly turned ends adapted to engage the ends of the pressure bar, said locking bar having a downwardly bowed center adapted to engage the central portion of the pressure bar, a pair of upwardly and outwardly extending spring fingers apertured for the reception of the posts, said spring fingers being secured adjacent the end portions of the locking bar inwardly of said posts, said spring fingers bearing against the inner sides of the said posts and forcing said posts against the outer side of the walls of the apertures in said locking bar.

In testimony that I claim the foregoing I have hereunto set my hand at Milwaukee, in the county of Milwaukee and State of Wisconsin.

OSCAR LOEWENBACH.
